UNITED STATES PATENT OFFICE.

ISAAC E. PALMER, OF MIDDLETOWN, CONNECTICUT.

DESIGN FOR A HAMMOCK-SUPPORT.

SPECIFICATION forming part of Design No. 26,258, dated November 10, 1896.

Application filed September 16, 1893. Serial No. 485,726. Term of patent 14 years.

To all whom it may concern:

Be it known that I, ISAAC E. PALMER, of Middletown, in the county of Middlesex and State of Connecticut, have invented and produced an original Design for Hammock-Supports, of which the following is a specification, reference being had to the accompanying drawings, forming a part thereof.

Figure 1 is a view of the support in side elevation, and Fig. 2 is an end view.

My design relates to a hammock-support comprising a ridge-pole and legs at the opposite ends of the ridge-pole for supporting it; and its leading feature consists in the peculiar shape of the ridge-pole and legs, the ridge-pole presenting in side elevation an elongated skeleton of diamond shape, and the support-

ing-legs presenting in side elevation a general **Y** shape.

A represents the ridge-pole as a whole, *a a* 20 the diverging sides from one vertex of the diamond, and *a' a'* the diverging sides from the opposite vertex of the diamond.

B represents a leg as a whole, and *b b'* the diverging parts which produce the upper portion of the **Y**.

What I claim is—

The design for a hammock-support as herein shown and described.

ISAAC E. PALMER.
